UNITED STATES PATENT OFFICE.

BENJAMIN O. FANSLOW, OF WHITE PLAINS, NEW YORK, ASSIGNOR TO NEW ERA MFG. CO., OF NEW YORK, N. Y., A CORPORATION OF NEW YORK.

CHECK-PROTECTING MACHINE.

1,333,108.

Specification of Letters Patent.

Patented Mar. 9, 1920.

Application filed June 3, 1918. Serial No. 237,969.

To all whom it may concern:

Be it known that I, BENJAMIN O. FANSLOW, a citizen of the United States, residing in White Plains, county of Westchester, and 5 State of New York, have invented a new and useful Improvement in Check-Protecting Machines, of which the following is a description.

The invention relates to new and useful 10 improvements in check protecting machines, and more particularly to a machine of the type known as check writers.

An object of the invention is to provide 15 a machine of the above type which is strong, durable, compact and easily operated, and wherein the various parts are positively held in proper timed relation to each other.

A further object of the invention is to provide 20 a machine of the above type, wherein the printing wheel is mounted in a cross head reciprocating in a vertical plane, and wherein the printing wheel is turned for bringing any desired row of type in printing position, by means of a shaft mounted 25 independently of the cross head, and also wherein means is provided for locking the printing wheel when disconnected from its operating shaft by the movements of the cross head.

30 A further object of the invention is to provide a machine of the above character with a gage member for controlling the feeding movements of the check, which gage member is mounted independently of the 35 cross head and which is locked independently of the printing wheel by means operated with the cross head, so that the printing wheel and gage member can not possibly turn and get out of proper timing relative 40 to each other when the printing wheel is disconnected from the operating means.

A still further object of the invention is to provide 45 a pair of guides which are adjustable on the bed of the machine relative thereto and to each other for guiding the check through the machine, which permits the check being centered anywhere in the machine relative to the printing position.

With the above objects in view, and others 50 which will be detailed during the course of this description, my invention consists in the parts, features, elements and combinations thereof hereinafter described and claimed.

55 In order that my invention may be clearly

understood, I have provided drawings wherein:

Figure 1 is a front elevation showing a 60 form of check-writer embodying my invention;

Fig. 2 is a horizontal section of the machine just above the crank-shaft;

Fig. 3 is a front elevation of the machine 65 with the face-plate removed and the printing-wheel in its position of upper extreme;

Fig. 4 is a view similar to Fig. 3, with the printing-wheel also removed, excepting a small section thereof at the bottom for the purpose of showing the coöperation of the locking means, and the position of the parts 70 being shown as when the printing-wheel is at the lower extreme;

Fig. 5 is a section on the line 5—5 of Fig. 1, the printing-wheel being shown at the 75 upper extreme;

Fig. 6 is a similar sectional view showing the printing-wheel at the lower extreme;

Fig. 7 is a top plan of the bed of the machine showing the guides set thereon and another position thereof being shown by 80 dotted lines; and

Fig. 8 is a section substantially on the line 8—8 of Fig. 7 showing the means for supporting and adjusting the platen.

Referring to the drawings, the numeral 1 85 indicates the bed of the machine, 2 the feet or pads on the bottom thereof, of which there may be three or more, 3 the frame of the machine mounted on the bed and suitably secured thereto and spaced therefrom 90 to form a check passage therethrough, 4 the dialed face-plate which is secured removably in position, by any suitable means, 5 the pointer which coöperates with the dial, and which is supported centrally on the hub 6 of 95 the printing-wheel 7, carrying type-blocks 8, said printing-wheel being mounted to turn with the shaft 9, journaled in the cross-head or plunger 10, guided for right-line reciprocations in the ways 11 of the 100 frame 3. The shaft 9, at its inner end, has secured thereto the gear 12 which meshes with the gear 13 carried by the shaft 14, journaled in the depending lug or member 15 at the top of the frame, said shaft, at its 105 other end, carrying the feed gage-member 16, the face of which is provided with a plurality of shoulders or projections 17 of varying height corresponding with the length of the word on the type-blocks 8 of the print- 110

ing-wheel. The spur-wheel 18 carried by the shaft 19 meshes with the gear-wheel 13, whereby the gage-member and the printing-wheel may be simultaneously rotated upon manipulation of the knob 20 at the outer end of the shaft 19, the latter, at its inner end, being journaled in the lug 15, and near its handle in the frame of the machine, longitudinal movement of said shaft 19 being prevented by the stop-collar 21, secured thereto so as to prevent the spur-wheel from being moved out of mesh with the gear-wheel.

The cross-head or plunger 10 is provided on its upper surface at opposite sides with anti-frictional rolls 22, which engage cams 23, depending from the yoke 24 secured to the crank-shaft 25, journaled at one end in the frame 3 and held from longitudinal movement in one direction by the screw 26, the head of which engages the outside of the frame, and the opposite end of which shaft is journaled in the frame and provided outside the latter with the crank 27, having a handle 28, and the collar of which engages the outside of the frame to prevent longitudinal movement of the shaft in the other direction. By means of the crank 27, the printing-wheel is driven into coöperation with the platen 29 set in a slot 30 in the bed of the machine. Viewing Fig. 8, it will be seen that the platen may be vertically adjusted in the bed by means of the hollow screws 31 threaded into the bed, and the upper ends of which form a bearing or rest for the bottom of the platen. By adjusting the screws in the bed, the platen may be lifted from the latter, and, when so lifted, the ends of the hollow screws become the bed or support for the platen. The platen is secured to the hollow screws by means of the screws 32 extending through the ends of the hollow screws into the platen. Thus all inequalities in the platen may be compensated for, and the platen may be raised or lowered relatively to the printing-wheel so as to enable the impression made on the paper by the type-blocks on the printing-wheel to be more or less sharp or deep, this function having particular reference to printing-blocks and platens, the coöperating surfaces of which are scored, ridged and grooved, pointed or otherwise treated to cut, macerate, puncture or otherwise break the fiber of the paper, so as to enable the ink spread upon the type-blocks to penetrate and saturate the fiber of the paper.

The printing-wheel, when in its lowermost or printing position in coöperation with the platen, is locked from rotation so that, when a type-block is once set for printing and the operation is started, it can be neither turned nor jarred so as to disturb the proper coöperative relation of the

printing-block relatively to the platen. In the uppermost position of the printing-wheel, it is free to turn through the medium of the knob 20 and described gear, so as to enable the proper type-block to be set for a printing operation. These functions are accomplished by means of a train of mechanism including a locking lever fulcrumed between its ends, as at 33, between a pair of lugs 34 depending from the cross-head or plunger 10, the front end 35 of said lever extending within the printing-wheel into position to coöperate with slots between a plurality of circumferentially arranged ribs or lugs 36 on the inner surface of the wheel-flange. The rear end 37 of the locking lever has a laterally projecting lug 38 extending into an aperture in the lower end of a swinging arm 39 journaled upon the shaft 40 mounted in the frame 3 at one end and at its other end upon an adjustable screw 41 screwed into the frame 3 and extending into said shaft. When the plunger is depressed to depress the printing-wheel, as from the position of Fig. 5 to that of Fig. 6, the lever fulcrum is carried downwardly resulting in depressing the front end 35 of said lever into a slot between lugs 36, the opposite end 37 of the lever remaining elevated by reason of its connection with the arm 39, which merely swings slightly upon the shaft 40 in order to compensate for the movement of the rear end of the lever. The locking means, therefore, is a lever of the third order, the power being imposed at 33 and the fulcrum being at 38.

To prevent the gage-member 16 rotating after it has been set and during the downward movement of the plunger 10, a locking mechanism is provided consisting of circumferentially arranged teeth 42 on the gage-member 16 with which coöperates a dog 43 on the locking lever 44, pivoted at 45 to the back of the frame of the machine, said locking lever having an open end, obliquely extending slot 46 forming a prong 47 with which engages a pin 48 carried by the cross-head or plunger 10 at one side thereof and extending rearwardly into engaging position, as shown in Fig. 2. The lower end 49 of the locking lever is squared or flat, (dotted lines, Fig. 4) so as to cause the pin in its descent to push the dog 43 into engagement with the teeth on the gage-member and hold the same there while the printing operation is taking place, and also during the feeding operation upon the check after the printing operation has been completed and while the printing-wheel is returning to its uppermost position. Just before the printing-wheel reaches its uppermost position, the pin 48 will engage the prong 47 and shift the locking lever laterally, so that the pin may enter the slot 46, 130

thus removing the dog 43 from the ratchet teeth, enabling free movement of the latter and the gage-member 16.

It will be noted from the above description that the printing wheel is mounted in a cross head which reciprocates in a vertical plane, while the operating shaft therefor is mounted independently of the cross head, so that the gear on the cross head, 10 which rotates the printing wheel, moves out of mesh with the gear on the shaft for setting the same. In view of this disconnection of the printing wheel from its operating shaft and owing to the mounting of the 15 gage member independently of the cross head, two locking devices are provided—one of which automatically locks the gage member and the other automatically locks the printing wheel, and both of these locking 20 devices are operated by the cross head. This positive locking of the gage member and the printing wheel insures that they will remain in proper timing relative to each other, so that when the cross head is 25 again raised and the gear associated with the printing wheel brought into mesh with its operating gear on the setting shaft, the stops on the gage member will be properly associated with the respective type blocks 30 for which they are designed to coöperate in the feeding operation of the machine.

Inking rolls 50 are provided for inking the surfaces of the printing-blocks, whereby the printing function is accomplished, 35 said rolls being journaled upon pins 51 carried by levers 52 fulcrumed in the cross-head at 53. The inking rolls are held constantly yieldingly in engagement with the circumference of the printing-wheel by 40 means of the connecting coiled spring 54.

The bed of the machine, see Figs. 5 to 8, inclusive, is provided longitudinally thereof, near its rear edge and in its upper surface, with a groove 55, along which are adjusted check-guides generally indicated by 45 56. Each of said guides has a U-shaped, guiding portion 57 extending toward the front of the machine, the open side of which is toward the platen and forms a passage in 50 which an edge of the check is guided. On its bottom, each guide is provided with a plurality of lugs 58 preferably formed by depressing or striking up the metal of the guides, said lugs being of a form and size to 55 snugly fit within the groove 55 in the bed, whereby the guides are frictionally held in position with ability to be shifted readily toward and from the platen to any extent desired, according to the width of the check 60 to be printed. At their rear ends, each guide is spread out or enlarged at its bottom to provide a substantial surface upon which the check may rest, and the extreme rear end of said portion is upturned, as at 59, 65 for the purpose of enabling the edge of the

check, when inserted in the guides, to be deflected downwardly and properly through the guides to the front of the machine, this formation of the rear end of the guides also enabling the check to be held raised from 70 the bottom of the guides for ready engagement by the operator. On the outer side of each guide a thumb-piece or extension 60 is extended upwardly for manipulation of the guide; and, in order to frictionally hold the 75 guide in position and also depressed with its lugs in the groove 55, spring tongues 61 are formed as rearward extensions of the upper member of the U-shaped portions 57, said tongues engaging frictionally and with 80 tension the lower edge of the back of the frame 3, as at 62, it being understood that the frame 3 is separated from the bed from side-to-side and front to rear to form a passage for the check 63, the direction of feed 85 of which is indicated by the arrow, Figs. 5 and 6. The dotted lines, Fig. 7, show the closest position of adjustment of the two guides relatively to the platen and to each other, their further movement together being limited by the lug 64 extending upwardly from the groove 55 in the bed.

A feeding mechanism is provided which *per se* forms no part of this application, but is shown and claimed in my co-pending application Serial Number 237968, filed of even date herewith. The shoulders 17 of the gage-member 16, upon manipulation of the knob 20 to set the printing-wheel, are simultaneously shifted to proper position for coöperation 100 with the controlling arm 65, which is mounted to turn upon the shaft 40. The normal position of the controlling arm 65 is shown in Fig. 5 and tendency to maintain the same is produced by the spring 66 connected to the 105 hub of said arm and near the lower edge of the back of the frame 3. The dotted lines show a position of coöperation of the controlling arm with a gage-shoulder. An actuator 67 is also mounted to turn on the 110 shaft 40, and is caused to turn by lugs 68 extending from the rear of the plunger 10. The actuator drives a feed-arm 69, the lower end of which is bifurcated and coöperates with a pin 70, extending from a feed-slide 71 carrying a pivotally supported, spring-controlled feed-dog 72, the slide being mounted on the guide 73 at the forward end of which is mounted a pivotally supported, spring-controlled detent 74. The 115 dog and detent normally engage the upper surface of the check and, when the dog feeds the check, the detent permits it to pass; but, when the dog moves rearwardly over the check, the detent grips the latter and prevents it from moving. In the bed is set a ridged and grooved plate 75, located beside the platen and under the dog and detent for coöperation with prongs on the executive 120 ends of the latter, Figs. 3 and 4. 125

As shown in Fig. 3, a combined presser and stripper 76 is secured to the back of the frame and has members 77 extending over the bed in position to engage the top of the check on both sides of the platen to hold the check on the bed and prevent it from following the printing-wheel in its upward movement.

The foregoing detail description will enable the mode of operation to be readily understood: When the knob 20 is turned, the printing-wheel is turned and simultaneously therewith the feed controlling gage-member 16, this being a movement preliminary to printing and feeding and for the purpose of setting the proper type-block in position to coöperate with the platen and the proper gage-shoulder or projection of the gage-member in proper position for engagement with the controlling arm 65 of the feeding mechanism. The same operation shifts the pointer relatively to the dial, so that the operator can determine when the type-block desired is in printing position. At the same time, the type-blocks are inked by contact of the same with the oppositely disposed inking rolls yieldingly in engagement therewith. The proper printing member being in position for the printing operation, and a check having been inserted in the machine as shown in Figs. 5 and 6, between the guides 56, the latter having been adjusted to the proper position to engage the opposite edges of the check, the crank 27 is turned toward the operator, thus causing the yoke 24 and cams 23 to be turned, the latter operating upon the anti-frictional rolls 22 to depress the plunger 10 against the tension of the two springs 76 connected at their upper ends to the top of the frame of the machine and at their lower ends to the rear of the plunger 10. The printing couple,—the type-block and the platen,—are thus made to operate upon the check to print and macerate the same and simultaneously therewith the feed-slide is shifted from the position of Fig. 5 to the position of Fig. 6 preparatory to a feeding operation. The downward movement of the plunger operates upon the locking lever causing its forward end 35 to descend into a slot between ribs 36, thus preventing the printing-wheel from shifting relatively to the platen; and, at the same time, the pin 48 at the back of the plunger descends from the slot 46 in the detent 44 permitting the spur 43 to engage the ratchet 42 where it is held by the pin 48 engaging the lower end 49 of the detent. When the crank 27 is released, the springs 76 immediately elevate the printing-wheel and the actuator 67, causing the feed to take place, the movement of the dog 72 being controlled by the engagement of the arm 65, dotted lines Fig. 5, with the shoulder 65 in its path of movement. At the same time

the locking lever is raised so that its forward end 35 releases the printing-wheel, and the pin 48 is raised so as to engage the prong 47 and enter the groove 46 of the detent 44, thus shifting the spur 43 from the ratchet 70 releasing the gage-member. The printing-wheel and gage-member and pointer may now be again shifted by the knob 20, through the medium of the train of gearing preparatory to another printing and feeding operation.

Having thus described my invention, what I claim and desire to secure by Letters Patent is:

1. A check protecting machine including in combination, a frame, a printing wheel mounted in said frame adjacent the front of the machine and having its axis extending from front to rear of the machine, a rotary gage member mounted in said frame in rear of the printing wheel and with its axis extending from front to rear of the machine, an operating shaft located between said printing wheel and said rotary gage member and having gearing connection therewith for simultaneously rotating said printing wheel and rotary gage member.

2. A check protecting machine including in combination, a frame, a printing wheel mounted in said frame adjacent the front of the machine and having its axis extending from front to rear of the machine, a rotary gage member mounted in said frame in rear of the printing wheel and with its axis extending from front to rear of the machine, an operating shaft located between said printing wheel and said rotary gage member and having gearing connection therewith for simultaneously rotating said printing wheel and rotary gage member, a fixed shaft extending across the frame and beneath said first named shaft, a feeding mechanism, actuating devices therefor carried by said fixed shaft, and controlling devices for determining the length of the feed stroke carried by said shaft and coöperating with said gage member.

3. A check protecting machine including in combination, a frame, a printing wheel means mounted in said frame for supporting said printing wheel whereby it may be raised and lowered, means for raising and lowering the printing wheel, a platen co-operating with said printing wheel, a cross shaft mounted in fixed bearings in said frame, devices operated thereby for rotating said printing wheel, said devices being disposed so that when said printing wheel is lowered said devices will be disconnected from each other, and means actuated by the movements of the printing wheel up and down for locking the printing wheel from movement when said devices are out of engagement.

4. A check protecting machine including

in combination, a frame, a vertically reciprocating cross head mounted therein, means for raising and lowering the cross head, a printing wheel mounted for rotation in said cross head, a platen cooperating with said printing wheel, a lever pivotally carried by said cross head, projections on the printing wheel for receiving the end of the lever for locking the printing wheel from movement, and means engaging said lever for swinging the same when the cross head is raised and lowered.

5. A check protecting machine including in combination, a frame, a cross head mounted for vertical reciprocation in said frame, a roller located at each side of said cross head, a cross shaft mounted in said frame, means for oscillating said shaft, cams carried by the said shaft and making contact with the respective rollers for depressing the cross head, springs for raising said cross head, and a printing wheel journaled on said cross head.

6. A check protecting machine including in combination, a frame, a cross head mounted for vertical reciprocation in said frame, a roller located at each side of said cross head, a cross shaft mounted in said frame, means for oscillating said shaft, cams carried by the said shaft and making contact with the respective rollers for depressing the cross head, springs for raising said cross head, a printing wheel journaled on said cross head, and inking rolls mounted on said cross head and movable up and down therewith, said inking rolls being disposed so as to make contact with the printing wheel.

7. A check protecting machine including in combination, a frame, a vertically reciprocating cross head mounted in said frame, a printing wheel carried by said cross head, a shaft mounted in said frame independent of the cross head, a gear carried by said shaft, a gear fixed to the printing wheel, and meshing with said gear on the shaft, said gears being so disposed as to be disconnected when said cross head is lowered, and means actuated by the movements of the cross head for locking the printing wheel from movement when said gears are out of mesh.

8. A check protecting machine including in combination, a frame, a vertically reciprocating cross head mounted in said frame, a printing wheel carried by said cross head, a shaft mounted in said frame independent of the cross head, a gear carried by said shaft, a gear fixed to the printing wheel, and meshing with said gear on the shaft, said gears being so disposed as to be disconnected when said cross head is lowered, means actuated by the movements of the cross head for locking the printing wheel from movement when said gears are out of mesh, a feeding mechanism for feeding the check, a rotary gage member associated with said feeding mecha-

nism, means for connecting the said rotary gage member with said shaft, whereby the gage member and printing wheels may be simultaneously rotated, and means operated by said cross head for locking the gage member from movement when the said gears are out of mesh.

9. A check protecting machine including in combination, a printing wheel, means for raising and lowering the printing wheel, a shaft mounted independently of the raising and lowering means for the printing wheel, a gear carried thereby, means for rotating said shaft, a gear movable up and down with the printing wheel and meshing with the gear on the shaft, a feeding mechanism, a gage member associated therewith and mounted on said shaft, whereby the gage member and printing wheel may be simultaneously rotated, the gear associated with said printing wheel being moved out of mesh when said printing wheel is moved from its extreme upper position, means for locking said printing wheel when said gears are out of mesh, and independent means for locking the gage member when said gears are out of mesh.

10. A check protecting machine including in combination, a reciprocating cross head, a printing wheel mounted thereon, a feeding mechanism, a gage member associated with said feeding mechanism and mounted independent of said cross head, means for moving the cross head up and down, and means for locking said gage member from rotation when said cross head is moved away from its extreme upper position.

11. A check protecting machine including in combination, a frame, a shaft journaled in the upper end of said frame and extending transversely across the machine, a hand operated lever connected to the outer end of said shaft, a second shaft mounted in said frame and extending parallel with the first named shaft, and hand operating knob secured to the end of said last named shaft opposite the handle of the first named shaft, a movable cross head, a printing wheel carried thereby, means actuated by said first named shaft for moving the cross head up and down, a feeding mechanism, a gage member associated therewith, and means operated from said second named shaft for simultaneously rotating said gage member and said printing wheel.

12. A check protecting machine including in combination, a frame, a shaft extending transversely across said frame, an operating handle secured at one end thereof, a cross head mounted to reciprocate in said frame, devices for actuating the cross head from the shaft, a printing wheel journaled on said cross head and adapted to rotate about an axis at right angles to said shaft, a second shaft parallel with the first named shaft

having a hand operating knob on the opposite side of the machine from said handle, a gear wheel associated with said printing wheel, and a gear on said second shaft for 5 rotating said gear wheel.

18. A check protecting machine including in combination, a frame, a shaft extending transversely across said frame, an operating handle secured at one end thereof, a cross 10 head mounted to reciprocate in said frame, devices for actuating the cross head from the shaft, a printing wheel journaled on said cross head and adapted to rotate about an axis at right angles to said shaft, a 15 second shaft parallel with the first named shaft having a hand operating knob on the opposite side of the machine from said handle, a gear wheel associated with said printing wheel, and a gear on said shaft for 20 rotating said gear wheel, said gear wheel associated with said printing wheel being moved out of mesh with the gear wheel on said shaft when said cross head is lowered, and means operated in timing with the 25 downward movements of the cross head for locking the printing wheel when said gears are out of mesh.

14. A check protecting machine including in combination, a frame, a shaft extending 30 transversely across said frame, an operating handle secured at one end thereof, a cross head mounted to reciprocate in said frame, devices for actuating the cross head from the shaft, a printing wheel journaled on said cross head and adapted to rotate about an axis at right angles to said shaft, a second 35 shaft parallel with the first named shaft having a hand operating knob on the opposite side of the machine from said handle, a gear 40 wheel associated with said printing wheel, and a gear on said shaft for rotating said gear wheel, said gear wheel associated with said printing wheel being moved out of mesh with the gear wheel on said shaft when said cross head is lowered, means operated in 45 timing with the downward movements of the cross head for locking the printing wheel when said gears are out of mesh, a gage member mounted independent of the printing 50 wheel, and means for rotating said gage member from said second named shaft.

15. A check protecting machine including in combination, a frame, a shaft extending transversely of the frame at the upper end 55 thereof, a handle secured to one end of said shaft, a second shaft mounted in said frame parallel with the first named shaft and having a hand knob at the opposite side of the machine from said handle, a cross head, 60 means operated by said first named shaft for raising and lowering the cross head, a printing wheel located in front of the cross head and journaled thereon, gears for connecting the printing wheel to said second named 65 shaft whereby said printing wheel may be

rotated when the cross head is in raised position, said gears being disposed so as to move out of mesh when the cross head is lowered, and means for locking the printing wheel when said gears are out of mesh.

16. A check protecting machine including in combination, a frame, a shaft extending transversely of the frame at the upper end thereof, a handle secured to one end of said shaft, a second shaft mounted in said frame 70 parallel with the first named shaft and having a hand knob at the opposite side of the machine from said handle, a cross head, means operated by said first named shaft for raising and lowering the cross head, a printing wheel located in front of the cross head and journaled thereon, gears for connecting the printing wheel to said second named shaft whereby said printing wheel may be rotated when the cross head is in 75 raised position, said gears being disposed so as to move out of mesh when the cross head is lowered, means for locking the printing wheel when said gears are out of mesh, a feeding mechanism, a rotating gage member 80 associated therewith and located in rear of said shafts, and devices for rotating said gage member from said second named shaft.

17. Means for adjusting the position of a platen in a check protecting machine comprising a bed or support having a recess, a platen set in said recess, a plurality of hollow screws threaded into the bed and projecting into the recess for co-operation with the platen, each of said hollow screws being provided with means whereby the platen 95 may be secured thereto.

18. Check guiding means for a check protecting machine comprising a base having a groove therein, a pair of guiding devices 105 each substantially U-shaped in cross section, and each being provided with a lug adapted to enter the said groove and slide frictionally therein; and each of said devices being provided with means at its rear end for 110 shifting the same on the said bed.

19. A check guide for check protecting machines having an elongated U-shaped member and a substantially flat member at the end of the U-shaped member, said flat 115 member having its rear end upturned whereby to deflect the check into the elongated member.

20. A check guide for check protecting machines comprising an elongated U-shaped member, a flat member at one end thereof having an upturned manipulating member, and an upturned check deflecting member.

21. A check guide for check protecting machines comprising a substantially U-shaped elongated member, a substantially flat member at one end thereof, and a spring tongue in extension of the top of the U-shaped portion.

BENJAMIN O. FANSLOW.
